REST FOR ELECTRIC IRONS

Filed May 13, 1929

FIG 1

FIG 2

FIG 3

Inventor

Charles D. Andrea,

By his Attorney

Henry J. Schmidt.

UNITED STATES PATENT OFFICE

CHARLES D. ANDREA, OF OZONE PARK, NEW YORK

REST FOR ELECTRIC IRONS

Application filed May 13, 1929. Serial No. 362,555.

My invention relates to rests or stands for electric irons of the kind on which the iron may be placed while still hot, and it has for its main object to provide a rest which will positively eliminate all danger of the iron being upset or displaced therefrom. A further object is to provide a rest which may be conveniently hung on a wall so as to be out of the way and on which the electric 10 cord may be wound so as to prevent it from breaking or kinking. A still further object is to provide a device of simple, inexpensive construction and pleasing appearance.

These and other objects and advantages 15 will be readily understood from the following description and from the accompanying drawing of a preferred embodiment but it will be noted that certain modifications might be made without departing from the scope of the invention. In the drawing—

Fig. 1 is a front elevation of the rest showing an electric iron supported therein,

Fig. 2 is a side elevation, and

Fig. 3 is a top view.

Referring now to all the views, simultaneously, the rest, which is preferably made from one single piece of sheet metal, consists of a rear wall 10, side walls 11, front walls 12 and a bottom 13. The front walls are 30 curved rearwardly, as plainly shown at 14 in Fig. 3, and the free ends 15 of these walls are curved as shown. It will be seen that this construction forms what may be called a pocket into which the body of the iron 35 fits.

The handle 17 projects through the opening 18 which is formed between the curved walls 14. By curving these walls, as shown, the handle may conveniently be grasped by 40 the user. To accommodate the attachment plug 19, the bottom is cut between the walls 14 as shown at 20. One or more holes 21 are drilled or punched in the rear wall so that the rest may be secured on a wall by 45 means of screws or other securing means.

To prevent scorching of the wall when the iron is inserted while hot, a sheet of asbestos 22, or other heat resisting material, is secured on the back of the rear wall in any 50 suitable manner. The rear, side and front

walls are angular on top so that their heights decrease, gradually, from the center of the rear wall to the points 15. For the purpose of ornamentation, these edges are also scalloped.

To prevent the cord 23 from kinking or breaking and to provide a neat and convenient means for holding this cord, hooks 24 are secured on one of the side walls and on these the cord is wound.

Having described my invention, what I claim as new and wish to protect by Letters Patent is:

1. In a device of the class described; a receptacle formed of a rear wall, two side walls, and a bottom plate; the ends of said side walls bent towards each other to form front walls and the extreme ends bent inwardly towards the rear wall to form stops; a space being provided between the rearwardly extending parts to allow the handle of an iron to project therebetween; and a hole provided in the rear wall near its upper edge by which the device is suspended so that an iron inserted in the device will rest 75 with its heel on the bottom plate.

2. In a device of the class described; a receptacle formed of a rear wall, two side walls, and a bottom plate; the ends of said side walls bent towards each other to form front 80 walls but terminating equidistant of the axial center of the receptacle to form an opening through which the handle of an iron may project; and a hole provided in the rear wall near its upper edge by which the device is suspended so that an iron inserted in the device will rest with its heel on the bottom plate.

CHARLES D. ANDREA.
